(57) **CLAIM**

The ornamental design for a multi-piece food product, as shown and described.

DESCRIPTION

FIG. 1 is an enlarged perspective view of a multi-piece food product showing our new design;

FIG. 2 is a top plan view thereof;

FIG. 3 is a bottom plan view thereof;

FIG. 4 is a front elevational view thereof; and

FIG. 5 is a left side elevational view thereof.

FIG. 6 is an enlarged perspective view of the second embodiment of a multi-piece food product showing our new design;

FIG. 7 is a top plan view thereof;

FIG. 8 is a bottom plan view thereof;

FIG. 9 is a front elevational view thereof; and

FIG. 10 is a left side elevational view thereof.

FIG. 11 is an enlarged perspective view of the third embodiment of a multi-piece food product showing our new design;

FIG. 12 is a top plan view thereof;

FIG. 13 is a bottom plan view thereof;

FIG. 14 is a front elevational view thereof; and,

FIG. 15 is a left side elevational view thereof.
